(57) CLAIM

The ornamental design for beverage package, as shown and described.

DESCRIPTION

FIG. 1 is a pictorial view of a filled beverage package of the present invention, the shading indicating shape;

FIG. 2 is a front view thereof, the back view being identical to the front;

FIG. 3 is a side view thereof, both side views being the same;

FIG. 4 is a top view thereof;

FIG. 5 is a bottom view thereof;

FIG. 6 is a pictorial view of a filled beverage package according to a second embodiment of the present invention, the shading indicating shape;

FIG. 7 is a front view thereof, the back view being identical to the front;

FIG. 8 is a side view thereof, both side views being the same;

FIG. 9 is a top view thereof; and,

FIG. 10 is a bottom view thereof.

The broken line showing is for illustrative purposes only, and forms no part of the claimed design.
